UNITED STATES PATENT OFFICE.

J. B. TINKELPAUGH, OF HASTINGS, MINNESOTA.

HAME-FASTENING.

Specification forming part of Letters Patent No. 42,651, dated May 10, 1864.

To all whom it may concern:

Be it known that I, J. B. TINKELPAUGH, of Hastings, in the county of Dakota and State of Minnesota, have invented a new and useful Improvement in Adjustable Hame-Fasteners; and I do hereby declare that the following is a full and exact description thereof, reference being had to the accompanying drawings and letters of reference marked thereon, forming a part of this my specification, in which—

Figure 1 is a longitudinal section of my improved adjustable hame fastener; Fig. 2, a cross section; Fig. 3, a plan view, and Fig. 4 a front elevation.

The object of my invention is not only to provide the means whereby harness-hames may be readily adjusted and secured to their collars, but also secure its operative or working parts against derangement from the collection of dirt or other refuse matter within the implement, while at the same time great strength is secured at a point which receives a heavy draft of the animal upon which it is in use.

For this purpose I construct a hollow or tubular metallic support, A, open at both ends, into one end of which the hook b is screwed, as clearly shown in Fig. 1, while the opposite end receives a sliding rod, c, with its outer extremity hooked, as at b', to correspond with the hook b. The hooked rod c is made to closely fit within the tube A, and when inserted within the tube to its greatest extent, occupies about three-fourths of the length of the tube. In the upper portion of rod c notches, as at i, are cut therein, into which a catch, k, is made to engage by the operation of the spring l, as indicated in Fig. 1, whenever the rod is inserted within the tube, the point of the catch k, as at k', passing through a suitable opening in the side of the tube A in order to seat itself in the notches i of the rod c within the tube, during the act of insertion or withdrawal of the rod.

As clearly indicated in Fig. 1, a longitudinal slot or recess is made upon the outside of the tube A of proper form to receive the catch k and spring l, and partially inclose them therein, the catch being pivoted to the tube, as at m, and the spring secured to the bottom of the longitudinal slot or recess with a screw, n, as represented.

Thus constructed, it will be observed that in the operation of my improved hame-fastener that portion of the tube A which receives the rod c is so inclosed as to practically protect itself from the entrance of dirt and refuse matter, the collection of which in the notches i, or in contact with the point k' of the catch k, would impede or disarrange its proper working.

It will also be seen that the main or supporting portion of my hame-fastener, being made of tubular form, imparts great strength to the whole device, thus avoiding a liability to break under a heavy shaft, and that, as the hook b is constructed of a material separate from the main body or support A, it can, if broken, have its place supplied by a new hook without necessitating the loss or throwing aside of the main portion A of the hame-fastening.

Having thus described my invention, what I claim as new, and desire to secure by Letters Patent, is—

1. The tubular support A, in combination with the notched rod c, substantially as and for the purpose described.
2. A metallic tube, A, for the purpose of a support and protection to the operative parts of a hame-fastener, substantially as described.
3. The removable hook b, in combination with the tube A, substantially as described.

J. B. TINKELPAUGH.
